ROOF CONSTRUCTION

Frank B. Wallace, Phoenix, Ariz.

Application January 9, 1939, Serial No. 249,870

6 Claims. (Cl. 108—6)

My invention relates to the use of concrete in a roof construction in which a relatively thin slab of concrete is used to form a run-off surface for the water and has a finished structure simulating shingles. There have been patents issued and attempts to make concrete roofs of a somewhat similar thin slab type of formation however difficulties have been experienced in the cracking of the cement as it is almost impossible to prevent the thin material from cracking. However in my construction I make provision for the cracks to develop at special and designated thin or weakened places so that such cracks are substantially no detriment to the completed roof. My type of molding or laying of the cement to form the simulation of shingles is quite distinct from concrete or similar roof constructions in which the finished surface is marked off by lines or similar devices to represent by such markings the outline of shingles.

A further object and feature of my invention is the employment of the concrete roof slabs with the shingle type of upper surface to be applied to a wood construction of roof in which the ordinary type of wood sheeting is laid on the rafters, this having the desired slope. With my construction it is desirable to have a good type of water-proof covering on the sheeting. There are many types of constructions suitable for this purpose however it is necessary that this covering is not perforated by any nail holes or the like which would let water in a rainy period or the water melted from snow seep through to the wood sheeting. It is also highly desirable that the water-proof covering be of material which is proof against rot on account of a certain amount of dampness being retained in the concrete during rainy or damp weather and the material being subject to changes of temperature. I therefore recommend either roofing felts with coal tar coating or a roofing having a cap sheet of an asbestos type of felt. Another excellent water-proofing covering is the ordinary galvanized iron sheets such as used to form galvanized iron roofs.

My invention contemplates after the construction of the sheeting and the water-proofing portion of the roof, the laying of a wire or a similar concrete reinforcement. This is usually a special wire mesh construction such as used in stucco work and it is preferably stretched over the roof surface and attached to as few places as possible, thus with a ridge type of roof the reinforcing wire may be attached adjacent the eaves and stretch over the ridge from one eave to the other and in a single slope or shed type of roof the

reinforcing wire need only be attached adjacent the top and the eave portion of the roof, thus avoiding nail holes through the water proofing material.

The next procedure in constructing my roof is to form a covering for coating designated in the trade as a scratch coat of concrete. This embeds the wire reinforcing so that such wire mesh material forms a thorough bonding and reinforcing for the concrete slab forming the scratch coat. This scratch coating is usually somewhat rough on its upper surface and such upper surface is approximately parallel to the wood sheathing underneath.

In the feature of my invention in forming the simulation of the shingle, these are molded directly on the scratch coat in such a manner that the simulated shingles have the taper with the thin upper edge portion and a thick lower edge, thus giving the pleasing relief of the butt end of shingles. In one procedure I employ a fork shaped mold which starting adjacent the ridge of the roof or the upper portion is used to mold the successive shingles, these being trowelled off to a taper and the prongs of the mold forming spaces between adjacent shingles in the same row. In another form of my invention a form strip is laid on the scratch coat. This is of the desired thickness to form the thick base of a shingle. A strip is then trowelled having the desired slope of the shingle surface and to give the appearance of individual shingles I employ grooves usually cut by pressing a blade the same length as the width of the shingle and therefore forming the groove the width of the exposed shingle. Thus a characteristic of the shingle finish is that at each layer of shingles or at each individual shingle there is a weakened or thin section adjacent the thin or upper part of the shingle construction and this is the part that is most likely to crack in any cracking of the cement but these cracks are usually so fine that they are more or less immaterial so far as leakage of water is concerned. Further, where the individual shingles are molded they are of such small size that the cracks do not readily develop in the shingle construction itself. In the form in which the grooves are trowelled, these trowel lines form a slight weakening of the shingle slab so that if cracks develop they are produced in straight lines in alignment with the slope of the roof. When the scratch coat is cured to a sufficient degree and the concrete shingles molded thereon, there is a proper bond between the shingles and the scratch coat, thus forming a

substantially impervious concrete roof construction over the water-proof composition roofing and the wood sheeting.

A characteristic feature of my invention is that the top surface construction simulating shingles is molded from the upper portion of the roof, that is, the portion adjacent the ridge downwardly towards the lower portion of the roof to the eave. This is in contradistinction to the usual manner of laying shingles. Thus an upper row of the roof surface simulating shingles is formed and then the next lower row with the thin edge of such lower row butting against and bonding with the thick edge of the row above, the surface of each row thus being finished off or troweled on a slope relative to the roof lesser than that of the roof considered as to a horizontal plane, hence in one form of my invention where I employ a molding tool for each so-called shingle, the parallel tapered prongs of the tool which are connected to a thick base have the blunt ends of the prongs thrust against the lower thick edge of the shingle thereabove, the space between this butt of an upper shingle, the two prongs and the base of the tool are then filled with concrete which is struck off on a line with the upper surface of the prongs and the base thus forming an individual tapered shingle and these are made in successive rows. In another procedure, an upper panel is formed using a mold board which has an edge defining the thick or butt edge of the shingle. The concrete is then filled in between the upwardly facing edge of the mold board and the lower thick edge of the shingle next above. The panel is tapered as to thickness so that the upper panel presents a reveal edge facing downwardly. The upper panel then may be cut into by score lines running at right angles to the mold board and thus to the length of the panel.

My invention is illustrated in connection with the accompanying drawing in which

Figure 1 is a plan of a portion of a roof taken in the direction of the arrow 1 of Fig. 2, it being presumed that the roof has the usual slope.

Fig. 2 is a vertical section on the line 2—2 of Figure 1 in the direction of the arrows.

Fig. 3 is a plan of an individual shingle molding tool taken in the direction of the arrow 3 of Fig. 4.

Fig. 4 is a side elevation of the same tool taken in the direction of the arrow 4 of Fig. 3.

Fig. 5 is a plan of an alternative roof construction illustrating a part of the roof taken in the direction of the arrow 5 of Fig. 6.

Fig. 6 is a vertical section taken on the line 6—6 of Fig. 5 in the direction of the arrows.

Referring first to the construction of Figs. 1 and 2 requiring the use of the tools of Figs. 3 and 4, the roof has a layer of wood boards or sheathing 11, this being an ordinary construction and supported on rafters or the equivalent these not being illustrated. Laid completely over the top of the roof sheathing there is a covering of a waterproofing roof material or composition 12.

This, as above stated, may be made of ordinary roofing felt. It is, however, desirable that it have an adequate coating of tar or equivalent material. A better type of roofing is that which has a cap sheet of asbestos together with the sufficient amount of asphaltum. In view of the fact that this waterproofing layer is subsequently covered and thus out of contact with the air except such as can seep through the concrete and through the cracks in the sheathing the water-

proofing should be of a rot-proof type and all nail holes should be thoroughly covered and waterproofed.

Laid over the waterproofing cover I employ a reinforcement material 13. This is illustrated as the convenient wire mesh or similar material such as used in roofing or stucco sidings or the like. Where a ridge type of roof is used, it is desirable to attach the wire or similar reinforcement adjacent the eave of the roof and stretch it completely over the ridge to the opposite eave using as few nails as possible. With a shed-type of roof, the wire may be attached adjacent the upper edge and the eave.

A scratch coat 14 of concrete made in suitable mixture is then covered completely over the wire reinforcement and worked into this so as to completely embed such reinforcement in the scratch coat or concrete. The underside of the scratch coat therefore engages the surface of the waterproofing cover. Such scratch coat may be made and applied in the ordinary manner and is usually left somewhat rough on its upper surface. It is preferable where possible to mold the shingles prior to the complete setting of the scratch coat.

In Figs. 1 and 2 the shingles designated 15 are molded by the molding tool 20 illustrated in Figs. 3 and 4. This tool has a handle 21, a base molding straight section 22, and opposite tapered prongs 23. The prongs terminate in a thin vertical rectangular edge 24. They are relatively thick at the portion 25 adjacent the base 22. For convenience of manipulation, the handle may be parallel to the upper edge 26 of the prongs, the lower edge 27 then converging from the wide section 25 to the thin edge 24. The shingles or imitation shingles are molded separately, using the molding tool and starting with the row at the high point of the roof. The tool in use is illustrated in dotted lines in Fig. 1.

The ends 24 of the prongs are fitted against a straight surface at the ridge or the edge of previously molded shingles. The under edge 27 is placed flat on top of the scratch coat, then concrete is filled into the mold formed by the prongs 23 and the base 22. The surplus concrete is struck off with a toothed edged tool and is usually left rough. The upper edges 26 of the prongs form a guide in striking off the upper surface, and level with the upper edges 26 of the prongs of the tool. This construction therefore produces the shingles having the construction of a thin upper edge 30, a thick lower edge 31, a surface 32 having a slope which is not parallel to the surface of the scratch coat but is manifestly at a slightly less slope in reference to the horizontal. Each individual shingle has an edge line 33 on its opposite edges running in straight lines from the ridge or the upper edge of the roof. It is preferable to stagger the shingles as illustrated in Figure 1. There is a slight space indicated at 34 between the adjacent edges 33 of contiguous shingles. This may be designated as a vertical joint.

It will thus be seen that the construction has a complete layer of concrete formed in the scratch coat, the individual shingles each separated by the vertical joint but each row connected to the next adjacent upper or lower row 70 at the thin portion 30 upon the upper edge of each individual shingle. Therefore, should there be cracks developed in the shingle coating they are most likely to occur at the weakened lines adjacent the thick base 31 of each of the shin- 75

gles. Such cracks do not materially endanger the roof as to leakage of water as such water will reach the vertical joints 34 and hence flow downwardly to the next adjacent row of shingles. 5 When properly laid there is an adequate bond of the shingles with the scratch coat.

With the construction of Figs. 5 and 6, I employ a similar sheathing 11, waterproof covering 12, the wire fiber reenforcing and a similar scratch coat indicated at 13 and 14. In this case, however, the shingles are made in longitudinal rows by employing a straight molding board indicated at 40. Such molding board is preferably rectangular in cross-section and has 5 at least an upper vertical edge 41 of the same thickness as the base portion 42 of a row of shingles indicated at 43. The molding of the shingles is started from the upper portion of the roof, the mold board may be placed and located 10 in any desired manner, it being held down on the scratch coat preferably by suitable weights. The mold board, as illustrated, forms a straight lower edge for the shingles. These are then troweled so that their upper surface 44 has a lesser 15 slope than that of the upper surface of the scratch coat, the upper surface of the mold board preferably forming a guide line for the thick edge of the shingle. The workmen, as a rule, do not need any gauge for the thin edge of the 20 shingle.

When a row such as 44 has been completed of a sufficient length score lines 45 are cut which give the effect of vertical joints between the individual shingles. In this construction there is 5 no vertical joint which leads directly from the upper surface of the shingle or shingle row to the scratch coat as in Fig. 1. This construction likewise presents the shingles with a weakened portion adjacent the thin upper edge and 10 also weakened vertical lines 45. Hence, should any crack develop in the shingle coating such cracks are most likely to follow the weakened portion. It is obvious that in the construction of Figs. 5 and 6, it is not necessary that the mold 15 board or strip 40 be straight. This could be curved or of other desired shape and thus give a varying length to the different portions of each row of shingles. It will therefore be seen that by 20 my roof construction it has the adequate protecting features of a concrete roof together with the desirable appearance of a shingled roof, the thick butt ends of the shingles giving prominent and shadow lines desired for the architectural effect.

It is to be noted by my construction that 5 the so-called shingles do not overlap but are molded either as individual shingles in the construction of Figs. 1 and 2 or in rows of panels as in Figs. 5 and 6 starting from an upper part 10 of the roof and working down towards the lower portion. The rectangular ends 24 of the prongs of the tool of Figs. 3 and 4 therefore butt against the thick lower edge 31 of the row of shingles above that being molded. In the construction 15 of Figs. 5 and 6 the mold board 40 is successively positioned downward on the roof from a row or panel such as 44 on an upper part of the roof. The space then between the mold board and the 20 butt edge of the upper row or panel is then filled with concrete, this being struck off at the lower edge reveal with the mold board and becomes thinner towards the butt end of the panels next above. It will be apparent that this type of construction can be placed on roofs of either a 25 slight or a steep pitch and if desired could even

be made on vertical surfaces, the principle of operation from the upper portion downwardly being continued.

Various changes may be made in the details of the construction without departing from the 5 spirit or scope of the invention as defined by the appended claims.

I claim:

1. In the method of forming a self-hardening composition roof on an under-roof structure 10 comprising molding a panel row of shingles at an upper portion of the roof with the thick butt edge facing downwardly and the thin upper edge facing upwardly, then forming a lower panel row of shingles with the upper thin edge butting 15 against the thick butt edge of the panel row next above, then in successive similar panel rows continuing the covering of the roof, the successive panel rows being molded in a sequence from an upper towards a lower portion of the roof. 20

2. In the method of forming a self-hardening composition roof on an under-roof structure comprising molding a panel row of shingles at an upper portion of the roof with the thick butt edge facing downwardly and the thin upper edge 25 facing upwardly, then forming a lower panel row of shingles with the upper thin edge butting against the thick butt edge of the panel row next above, then in successive similar panel rows continuing the covering of the roof, the successive 30 panel rows being molded in a sequence from an upper towards a lower portion of the roof, molding each shingle of a panel in a separate mold defining the butt and the two side edges, the upper edge of the individual panel being defined 35 by the butt edge of the panel row next above.

3. In the method of forming a self-hardening composition roof on an under-roof structure comprising molding a panel row of shingles at an upper portion of the roof with the thick butt 40 edge facing downwardly and the thin upper edge facing upwardly, then forming a lower panel row of shingles with the upper thin edge butting against the thick butt edge of the panel row next above, then in successive similar panel rows continuing the covering of the roof, the successive 45 panel rows being molded in a sequence from an upper towards a lower portion of the roof, molding a panel row by defining the lower butt edge of such panel row and striking off the surface of 50 the composition at the desired height for such edge and forming the lower panel row each thinner at its upper portion where it abuts the panel row next above.

4. In the method of forming a self-hardening 55 composition roof comprising molding an upper panel row of the composition with a thick butt lower edge facing downwardly on the roof and a thin upper edge towards the upper part of the roof whereby the upper surface of the panel row 60 has a slope less than that of the roof on which the composition is laid, then continuing molding successively lower panel rows with each panel row having a thick lower edge and a thin upper edge, the upper edge engaging the thick butt 65 edge of the panel next above and bonding therewith.

5. In the method of forming a self-hardening composition roof comprising molding an upper panel row of the composition with a thick butt 70 lower edge facing downwardly on the roof and a thin upper edge towards the upper part of the roof whereby the upper surface of the panel row has a slope less than that of the roof on which the composition is laid, then continuing molding 75

- successively lower panel rows with each panel row having a thick lower edge and a thin upper edge, the upper edge engaging the thick butt edge of the panel next above and bonding therewith,
- 5 in forming each panel row molding individual shingles defined by a thick base and tapered side edges and forming spaces between the adjacent side edges of shingles by spacing the molded shingles in each panel row.
- 10 6. In the method of forming a self-hardening composition roof comprising molding an upper panel row of the composition with a thick butt lower edge facing downwardly on the roof and a thin upper edge towards the upper part of the
- 15 roof whereby the upper surface of the panel row has a slope less than that of the roof on which the composition is laid, then continuing molding successively lower panel rows with each panel row

having a thick lower edge and a thin upper edge, the upper edge engaging the thick butt edge of the panel next above and bonding therewith, molding each panel row between a mold board and the panel row next above in which the surface of each panel row is struck off the thickness of the mold board and tapers to the thick or butt edge of the panel next above, the thin edges of a lower panel row bonding with the thick edges of the panel row next above, then forming cut score lines at right angles to the thick butt edges of each panel row to simulate individual shingles between two cut score lines, the score lines being of shallow depth not greater than the reveal lower edge of an upper panel row in reference to the thin upper portion of the panel row next below.

FRANK B. WALLACE.
